DISPLAY STAND FOR PAMPHLETS OR THE LIKE

John F. Carvlin, San Francisco, Calif., assignor to Missionary Society of St. Paul the Apostle in the State of California, San Francisco, Calif., a corporation of California

Filed June 27, 1960, Ser. No. 61,121

Term of patent 14 years

(Cl. D80—9)

FIG. 1 is a front perspective view of a display stand for pamphlets or the like showing my new design, several of the pamphlet holders being omitted for the convenience of illustration;

FIG. 2 is a top plan view thereof, a portion of the stand being broken away for convenience of illustration;

FIG. 3 is an enlarged fragmentary perspective view of one of the pamphlet holders.

The dominant features of my design reside in full-line portions of the drawing.

I claim:

The ornamental design for a display stand for pamphlets or the like, substantially as shown and described.
